[57] CLAIM

The ornamental design for a handgrip for a hacksaw assembly, as shown and described.

DESCRIPTION

FIG. 1 is a right side elevational view of a handgrip for a hacksaw assembly showing our new design;
FIG. 2 is a front elevational view thereof;
FIG. 3 is a rear elevational view thereof;
FIG. 4 is a top plan view thereof;
FIG. 5 is a bottom view thereof;
FIG. 6 is a cross sectional view along the line 6—6 of FIG. 1; and,
FIG. 7 is a left side elevational view thereof, the broken line portions of the drawing being for illustrative purposes only and form no part of the claimed design.

FIG. 2

FIG. 1

FIG. 3

FIG. 5

FIG. 4

FIG. 6

FIG. 7
